United States Patent Office

Des. 212,055
Patented Aug. 20, 1968

212,055

MOVIE CAMERA

Dale R. Caldwell, Chicago, Ill., assignor to Argus Incorporated, Chicago, Ill., a corporation of Delaware

Filed Aug. 29, 1967, Ser. No. 8,414

Term of patent 14 years

(Cl. D61—1)

FIG. 1 is a side elevational view of the movie camera showing my design;

FIG. 2 is a front elevational view of the movie camera showing my design;

FIG. 3 is a rear elevational view of the camera; and

FIG. 4 is a top plan view of a camera.

The dominant features of my new design are shown in solid lines in the drawing.

I claim:

The ornamental design for a movie camera, substantially as shown and described.
